John E. Early

United States Patent Office.

JOHN H. BLOODGOOD, OF BRIDGEPORT, CONNECTICUT.

Letters Patent No. 103,131, dated May 17, 1870.

IMPROVED ROLLER FOR SASH-STRAP FOR CARRIAGES.

The Schedule referred to in these Letters Patent and making part of the same

To all whom it may concern:

Be it known that I, JOHN H. BLOODGOOD, of Bridgeport, in the county of Fairfield and State of Connecticut, have invented a new Improvement in Carriage-Doors; and I do hereby declare the following, when taken in connection with the accompanying drawings and the letters of reference marked thereon, to be a full, clear, and exact description of the same, and which said drawings constitute part of this specification, and represent in—

Figure 1, an inside view of the carriage-door;

Figure 2, a central section;

Figure 3, a sectional perspective view of the clamp; and in

Figures 4 and 5, similar construction of the same clamp.

This invention relates to an improvement in carriage-doors, the object being the arrangement of a device in combination with the strap by which the glass is raised, so that the glass may be supported at any desired elevation; and

It consists in the arrangement upon the door of a clamping device, through which the strap for raising the glass passes, constructed so as to grasp the strap or holder, and hold it at any position to which the glass may be raised.

A is the lower part of a carriage-door, of common construction.

B, the frame of glass, constructed to run up and down in the door, and provided with a strap, C, for raising the glass, in the usual manner.

As heretofore constructed, it has been necessary that the glass be either clear down or clear up, there being no intermediate means for sustaining the same.

To do this, I arrange a clamping device upon the door, consisting of the fixed bar *a* and cam *d*, between which the strap *C* passes, as seen in figs. 1 and 2, the weight of the glass tending to close the cam, by draw-

ing over its inner surface, as seen in fig. 2, yet allow the strap to be freely drawn through, to elevate the glass.

To release the strap so that the glass may be lowered, I form an arm, *f*, (see fig. 3,) upon the cam, whereby it may be depressed, as denoted in broken lines, fig. 3, to free the strap and allow the descent of the glass.

In figs. 1, 2, and 3, I have shown the cam arranged to clamp the strap between it and a bar above; yet, if preferred, the cam may be arranged, as seen in figs. 4 and 5, to operate upon the bar below.

When the glass has been fully raised, as seen in fig. 2, and it is desirable to close the opening entirely, it is necessary to throw the glass onto the rabbet *n*.

To do this, I arrange a short strap, *m*, upon the lower bar of the glass, so that, by taking hold of the strap *m* and raising the glass, it will take the weight from the cam, consequently freeing the strap therefrom, and permit the glass to be thrown out, as denoted in broken lines, fig. 2.

By this construction, it will be seen that the glass may be held at any desired elevation, and the object of the invention fully accomplished.

I claim as my invention—

1. In the construction of carriage-doors, the combination of an automatic stop, catch, or clamp, with the glass frame-holder or strap, whereby the glass may be held in any desired position, substantially as shown.

2. In combination with the foregoing, the strap *m*, arranged upon the glass-frame, substantially as and for the purpose specified.

JOHN H. BLOODGOOD.
